Atty's:

UNITED STATES PATENT OFFICE.

JESSEE W. TURNER, OF LOUISIANA, MISSOURI.

DESIGN FOR A DISPLAY-STAND.

SPECIFICATION forming part of Design No. 24,476, dated July 16, 1895.

Application filed June 17, 1895. Serial No. 553,144. Term of patent 14 years.

To all whom it may concern:

Be it known that I, JESSEE W. TURNER, of the city of Louisiana, Pike county, State of Missouri, have invented a new and original Design for Shoe Display-Stands, of which the following is a full, clear, and exact description, reference being had to the accompanying drawing, forming a part hereof.

The drawing is a view in perspective of a display-stand embodying my design.

The leading feature of my design consists in a pillar surmounted by a crescent-shaped or semicircular body and an inclined plate having an irregular outline and top surface.

1 indicates the base of the pillar, said base being circular in contour and having a series of alternate annular projections and depres-

sions 2 upon its top surface. Extending upwardly from the center of said base is the pillar 3, the same having a series of alternate beads and depressions 4 formed near its lower end. Upon the upper end of this pillar 3 is the crescent-shaped or semicircular body 5, and upon said body 5 is an inclined plate 6, having an irregular outline and top face 7.

I claim—

The design for a display-stand, as herein shown and described.

In testimony whereof I affix my signature in presence of two witnesses.

JESSEE W. TURNER.

Witnesses:

FAYETTE TURNER,
J. D. MERIWETHER.
